UNITED STATES PATENT OFFICE.

LEWIS S. BORTREE, OF TOLEDO, OHIO.

CORSET.

SPECIFICATION forming part of Letters Patent No. 248,280, dated October 18, 1881.

Application filed May 14, 1881. (Model.)

To all whom it may concern:

Be it known that I, LEWIS S. BORTREE, of Toledo, in the county of Lucas and State of Ohio, have invented an Improvement in Corsets, of which the following is a specification.

The nature of this invention relates to certain new and useful improvements in corsets, whereby the hip-section is made adjustable to varying forms of wearers; and the invention 10 consists, first, in the peculiar construction and arrangement of the side pieces of the corset, in combination with an adjusting-strap of peculiar construction; second, in the peculiar construction of the stay at the bottom of the cut- 15 away portion of one-half the side piece; and, third, in the combinations of the parts, as more fully hereinafter described.

Figure 1 is an elevation of the side of the corset. Fig. 2 is a detached section of the stay 20 used at the bottom of the front half of the side, and Fig. 3 is a plan of the adjusting-strap.

In the accompanying drawings, which form a part of this specification, A represents the rear half of the side of a corset, B the front 25 half of the same, the two parts being joined by the vertical seam *a*, and at the front and rear to the back and front pieces of the corset.

In the part A bones are inserted, running from the top to the bottom of the piece vertically. The part B is cut away, as shown, such cut-away portion forming one-half of a 30 quadrant arch, and is provided with bones extending from the top edge of the corset to the bottom, each successive bone being longer than the one preceding it in the series. The lower 35 edge of this part B is bound with a thick corded binding, C, in order to make a bearing at that point, and preventing the edge of the corset from embedding in the flesh of the 40 wearer, such binding forming a cushion to prevent any such embedding, and at the same time it acts as a stay within which to secure the lower ends of the bones and prevent their cutting through the fabric.

45 A strap, D, the width of which at its base

is equal, or nearly so, to the distance between the lower edge, *b*, of the part A and the point *c*, where the parts A and B meet. This strap is made of this width and adjusted by means of the buckle or buckles E for the purpose of 50 covering the hip and preventing the flesh of the wearer from protruding through the opening, which frequently occurs in corsets cut away at the hip and adjustable by means of narrow strips or laces. This strap is also boned 55 vertically, as shown, to prevent its curling and to compel it at all times to hold its shape smoothly over the hip, and will be found almost as effectual in preserving the shape of the corset at this point as if there were no cut-away portion and the bones extended from the 60 top of the corset to the bottom.

If preferred, the side piece (represented in the drawings by the two parts A B) may be cut in one piece without departing from the 65 spirit of my invention, and no difficulty will be found in doing this so long as the vertical bones are employed and the front half of said side piece cut away, as shown in the drawings.

What I claim as my invention is—

1. In combination with the front half of a side section of a corset having its lower edge cut upon a curved line and provided with vertical bones of varying lengths, the corded binding C, substantially as and for the purpose 75 specified.

2. In a corset, a side section consisting of the parts A B, the latter being cut away on a curved line to form an opening between the two parts, in combination with a broad adjusting-strap, D, provided with vertical bones, 80 substantially as and for the purpose specified.

3. The corded binding C, in combination with a corset, substantially as and for the purpose specified.

LEWIS S. BORTREE.
